UNITED STATES PATENT OFFICE.

JOHN LALLY, OF BOSTON, MASSACHUSETTS.

COLUMN.

No. 901,453.

Specification of Letters Patent.

Patented Oct. 20, 1908.

Application filed August 22, 1907, Serial No. 389,638. Renewed August 4, 1908. Serial No. 446,960.

To all whom it may concern:

Be it known that I, JOHN LALLY, a citizen of the United States, residing at Boston, in the county of Suffolk and State of Massachusetts, have invented a certain new and useful Column, of which the following is a specification, reference being had therein to the accompanying drawing.

This invention relates to columns and the object of the invention is to provide a column of composite construction, embodying metal and concrete the elements of which are so combined and arranged that a continuous metal support is afforded throughout the entire length of the column thus adding greatly to the supporting and strain resisting properties of the column as a whole.

A further object of the invention is to provide a novel and effective construction of cap for the column embodying braces or brackets so combined with and related to the other parts of the cap that all parts are held firmly together without the aid of special bolts, rivets or the like.

With the above and other objects in view the nature of which will more fully appear as the description proceeds, the invention consists in the novel construction, combination and arrangement herein fully described, illustrated and claimed.

In the accompanying drawings:—Figure 1 is a vertical longitudinal section through a column embodying the present invention, showing a superimposed column section seated upon the column cap. Fig. 2 is a cross section through the same on the line 2—2 of Fig. 1. Fig. 3 is a cross section through the same on the line 3—3 of Fig. 1. Fig. 4 is a vertical longitudinal section through a superimposed column section, showing the manner of forming the pintle or steady pin thereon. Fig. 5 is a bottom plan view of the same. Fig. 6 is a cross section similar to Fig. 2, showing a slight modification in the construction of the cruciform core of the column. Fig. 7 is a detail cross section showing another way of fastening the braces or brackets in place.

The column comprises a base 1 which under the preferred embodiment of the invention has on its upper surface an annular flange 2 within which is received and confined the outer shell or column casing 3. This casing may be of any desired height according to the height of the column and

within said casing is placed a cruciform core or main body 4 having the radiating wings or flanges 5 which extend outward close to or in contact with the inner surface of the casing 3 as indicated in Fig. 2.

Mounted upon the upper end of the casing 3 and the corresponding end of the central core 4 is a cap rest 6 embodying upper and lower annular flanges 7 and 8, respectively, the bottom flange 8 encircling the upper end 65 of the casing 3, while the flange 7 encircles the bottom edge of the short superimposed outer casing 3', the two casing sections being thus centered relatively to each other.

Upon the top of the casing section 3' is 70 mounted a crown plate 9, the latter being formed with a series of holes in which are received the enlarged tapering heads 10 of a series of anchor bolts or rods 11, which pass downward within the casing sections, as 75 shown, and also through a corresponding series of holes formed in the cap rest 6, and if desired, also through a corresponding series of holes in the base 1. In case the bolts or rods 11 pass through the base 1, the latter is 80 countersunk in its lower side as shown to receive and let in the nuts 12, so that a smooth even surface is provided for the bottom of the column. In some cases, however, the bolts 11 may not extend as far as the base, in 85 which case the nuts 12' are threaded upon the bolts or rods just beneath the cap rest, as shown in Fig. 1. In this way all parts of the column are secured tied or bolted together and when the casing sections are filled with 90 concrete as indicated at 13, a thoroughly braced, fireproof column is the result.

The crown plate 9 is effectively braced by means of a series of triangular shaped brackets 14 which reach from the cap rest to the 95 crown plate, as shown; and each of said brackets is reduced at its inner edge to form a relatively narrow inwardly projecting shank 15, the latter passing through the casing section 3' and having its inner extremity 100 bent or extended laterally to form a hook or flange 16 which passes behind the adjacent anchor bolt or rod 11, the latter thus acting also as an anchor for the bracket. In reducing the bracket to form the retaining shank 105 15, a shoulder 17 is formed on the bracket, said shoulder bearing against the outer side of the casing section, as shown. In this way the brackets and casing section 3' mutually brace and support each other.

The superimposed column section embodies a casing 18 and a cruciform core 19 therein, said parts corresponding with the parts 3 and 4 above described. In order to 5 form a connection between the two column sections, a pintle or steady pin 20 is formed on the bottom of the superimposed column section, as shown in Figs. 1 and 4, the same being adapted to fit into a corresponding 10 socket or seat in the cap of the lower column section, as shown in Fig. 1. In forming this pintle, a series of bolts 21 are run lengthwise through the concrete filling 22 of the casing 18 and extended below the lower end of the 15 said casing, as seen in Fig. 4, while a small casing or sleeve 23 is placed around the projecting ends of said rods or bolts and filled with concrete as indicated at 24, the bolts 21 being thus firmly embedded in the concrete. 20 The pintle or steady pin 20 thus formed passes through a central opening in the crown plate 9 down into the socket provided therefor in the cap as seen in Fig. 1, thereby positioning and steadyng the upper column 25 section and preventing the said upper section from tilting upon the cap. If desired a socket tube 25 may be inserted in the socket opening as a lining for the same, as shown in Fig. 1, said tube extending from the 30 top of the crown plate to the top of the cap rest 6.

In Fig. 2 the cruciform core 4 is shown as made in one piece, while in Fig. 6, said core is shown as made up of several pieces or sections, one section extending diametrically 35 across the interior of the casing and two other narrower plates extending from the first mentioned plate outward to the casing. When filled with concrete all parts of the column 40 are held firmly thereby. Instead of providing the hooks or flanges 16, above described, and as shown in Fig. 3, the shanks 15 may be formed with eyes 26 to receive the bolts or rods 11, as shown in Fig. 7, the result being the same in both cases.

It will be seen that the anchor bolts or rods 11 hold or tie all parts of the column together and form a rigid structure; further that said bolts or rods are embedded in the 50 concrete filling of the column and themselves effectively held and braced at all points in their length thereby. A very strong, durable and fireproof column is thus obtained, this being accomplished without the use of 55 the many small bolts, rivets and like fasteners ordinarily employed.

I claim:—

1. A column comprising a casing, bolts extending lengthwise of the column, and a wrought-iron column cap embodying a 60 crown plate and braces therefor held in place by said bolts.

2. A column comprising a casing, bolts extending lengthwise of the column, and a wrought-iron column cap embodying a 65

crown plate held in place by said bolts, and braces held between the crown plate and the body of the column.

3. A column comprising a casing, a filling therefor, a base on which the casing rests, a superimposed rest, a cruciform core extending from the base to the superimposed rest, and means for tying the base and rest together. 70

4. A column comprising a casing, a filling therefor, a base, a cap rest mounted on the casing, a cruciform core embedded in the filling and extending from the base to the cap rest, a cap supported on the rest, and bolts extending lengthwise of the column, 75 embedded in the filling and holding the cap anchored on the column. 80

5. A column comprising a casing, a filling therefor, and a cap supported on the column and embodying a crown plate and brackets 85 for said plate having portions thereof embedded in the filling.

6. A column comprising a casing, a filling therefor, a cap rest, a cap mounted on said rest and embodying a crown plate and brackets interposed between the crown plate and cap rest and provided with shanks which enter the filling, and bolts embedded in the filling and engaging said shanks to hold the brackets in place. 90

7. A column comprising a casing, a filling therefor, a cap rest, a cap mounted thereon and embodying a casing, a filling therefor, a crown plate, brackets having portions thereof passing through the cap casing into the filling, and anchoring means within the cap casing engaging and holding the inwardly extending portions of the brackets. 95

8. A column comprising a casing, a filling therefor, a cap rest, a cap mounted on said rest and embodying a casing, a filling therefor, a crown plate, brackets interposed between the crown plate and cap rest and provided with shanks which enter the cap casing and are flanged or shouldered, and anchor 100 bolts embedded in the filling and engaging the flanges or shoulders of the said shanks. 110

9. A column comprising sections, one of which is provided with a pintle and another with a socket for said pintle, the pintle bearing section embodying a casing, a filling therefor, and a series of bolts or rods embedded in the filling and projecting beyond the end of the casing to form the pintle. 115

10. A column comprising sections, one of which is provided with a pintle and another with a socket for said pintle, the pintle bearing section embodying a casing, a filling therefor, and a series of bolts or rods embedded in the filling and projecting beyond the end of the casing, the said projecting ends of the bolts or rods being incased to 120 form the pintle of said section.

11. A column comprising sections one of which is provided with a pintle and another 125

with a socket for said pintle, the pintle bearing section embodying a casing, a filling therefor, a series of bolts or rods embedded in the filling and projecting beyond the end 5 of the casing, the said projecting ends of the bolts or rods being incased in concrete, and a metal casing or jacket encircling the projecting ends of the bolts or rods and the concrete incasing the same.

10 12. A column comprising sections one of which is provided with a pintle and another with a socket for said pintle, the pintle bear-

ing section embodying a casing, a filling for said casing, a cruciform core embedded in the filling, and a series of bolts or rods arranged 15 between the flanges of the core embedded in the filling and projecting beyond the end of the casing to form the pintle.

In testimony whereof I affix my signature in presence of two witnesses.

JOHN LALLY.
